BOX FOR SHAVING ACCESSORIES

Abraham Pavenick, New York, N. Y.

Application February 17, 1954, Serial No. 29,074

Term of patent 14 years

(Cl. D58—12)

To all whom it may concern:

Be it known that I, Abraham Pavenick, a citizen of the United States, residing at New York city, in the county of New York and State of New York, have invented a new, original, and ornamental Design for a Box for Shaving Accessories, of which the following is a specification, reference being had to the accompanying drawing, forming part thereof.

In the drawing:

Fig. 1 is a front perspective view of a box for shaving accessories showing my new design;

Fig. 2 is a side elevational view thereof, showing the box in open position;

Fig. 3 is a front elevational view thereof, showing the box in open position, and illustrating a mirror on the inside of the cover;

Fig. 4 is a top plan view thereof, showing the box in open position, and illustrating the compartments for a shaving brush and soap;

Fig. 5 is a bottom plan view thereof, showing the box in open position;

Fig. 6 is a rear elevational view thereof, showing the box in closed position; and

Fig. 7 is an enlarged cross-sectional view thereof taken substantially along the line 7-7 of Fig. 4.

I claim:

The ornamental design for a box for shaving accessories, substantially as shown.
